ABSTRACT

A process for the production of silver images according to the silver complex diffusion transfer process carried out in the presence of a hydroxylamine derivative developing agent and a (poly)amino(poly)carboxylic acid sequestering agent in acid form or in the form of a water-soluble salt is described. Better quality transfer images at substantially lower illumination levels are realized.

12 Claims, No Drawings

PROCESS OF FORMING SILVER TRANSFER IMAGES

The present invention relates to the formation of silver images by the silver complex diffusion transfer process.

Processes for forming silver images by the steps of image-wise exposure and development of a photosensitive silver halide element, the formation of a diffusible complex of unexposed silver halide in the unexposed areas of the said photosensitive element and the transfer by diffusion of said complex to an element, in superposed relationship with the photosensitive element, where the silver of said complex is precipitated or reduced to form a visible image, are now well known.

The element to which the silver complex is transferred is often referred to as the image-receiving element and generally comprises agents, known as development nuclei, that promote the precipitation of the silver of said silver complex.

According to a typical embodiment of the silver complex diffusion transfer process suitable for in-camera processing a composite material of unitary structure is used which comprises a photosensitive element, an image-receiving element and a viscous processing fluid contained in a pod or container. After image-wise exposure of the photosensitive element, which comprises a silver halide emulsion layer, the superposed elements i.e., the photosensitive element and the image-receiving element are guided between a pair of pressure rollers whereby the viscous processing liquid is spread as a uniform layer between the photosensitive element and the image-receiving element.

The photosensitive element and the image-receiving element are maintained in superposed relation for a determined period, usually of the order of 10 to 120 seconds, during which the exposed silver halide is developed, the undeveloped silver halide is converted into a water-soluble complex silver salt and the said complex is transferred through the layer of processing liquid to the silver precipitating layer of the image-receiving element where it is converted into a visible print. At the end of this contact period the photosensitive element is separated by stripping from the image-receiving element. Elements suitable for use in this silver complex diffusion transfer process are described in detail e.g., in U.S. Pat. No. 2,543,181 of Edwin H. Land, issued Feb. 27, 1951.

A wide variety of silver halide developing agents and silver halide complexing agents, are known for use in such diffusion transfer processes.

As silver halide developing agents it has been proposed amongst others in U.S. Pat. No. 2,857,276 of Edwin H. Land and Helen J. Tracy, issued Oct. 21, 1958 to use hydroxylamine and derivatives thereof, of which the oxidation products leave no residual stain in the positive silver image obtained. Hydroxylamine itself is less suitable because it gives rise to fog but the N,N-dialkylhydroxylamines such as N,N-diethylhydroxylamine and the heterocyclic N-hydroxylamines such as N-hydroxymorpholine, N-hydroxypiperidine and N-hydroxypyrrolidine disclosed in the above U.S. Pat specification are particularly suitable. Other hydroxylamine derivatives that have been proposed for use as silver halide developing agents and of which the

development activity is higher than that of the N,N-dialkylhydroxylamines include for example aminoalkylhydroxylamines, more especially N,N-dialkylhydroxylamines having in at least one of the N-alkyl groups an intralinear amino nitrogen atom, either cyclic or acyclic, examples of which can be found in U.S. Pat. No. 3,287,125, of Milton Green, Adnan A. Sayigh and Henri Ulrich, issued Nov. 22, 1966, alkoxy hydroxylamines, more especially N,N-dialkyl hydroxylamines of which at least one of the N-alkyl groups is substituted by alkoxy or alkoxy-alkoxy, examples of which can be found in U.S. Pat. No. 3,293,034 of Milton Green, Adnan A. Sayigh and Henri Ulrich, issued Dec. 20, 1966 and sulphone hydroxylamines, more especially N,N-dialkyl hydroxylamines having in at least one of the N-alkyl groups an intralinear sulphonyl (—SO₂—) group, examples of which can be found in U.S. Pat. No. 3,287,124 of Milton Green, Adnan A. Sayigh and Henri Ulrich, issued Nov. 22, 1966.

It has now been found when using, in a process for the production of silver images according to the silver complex diffusion transfer process, carried out developing agent, a photosensor element the presence of a hydroxylamine derivative as silver halide emulsion comprising a silver halide emulsion layer, and a (poly)amino(poly)carboxylic acid sequestering compound, in acid form or in the form of a water-soluble salt, transfer images are obtained of improved quality.

The use of (poly)amino(poly)carboxylic acid sequestering compounds, in acid form or in the form of a water-soluble salt, in a silver complex diffusion transfer process wherein use is made of a hydroxylamine developing agent is effective to give better quality transfer images at substantially lower illumination levels than are necessary in the absence of said compounds, without giving rise to a noteworthy decrease in maximum density of the images formed.

Therefore, in accordance with the present invention, there is provided a process of forming silver transfer images which comprises the steps of exposing a photosensitive element containing a silver halide emulsion layer and a (poly)amino(poly) carboxylic acid sequestering compound, in acid form or in the form of a water-soluble salt, developing the exposed photosensitive silver halide emulsion layer and forming a soluble silver complex of unexposed silver halide by treating the said photosensitive silver halide emulsion layer with an alkaline processing fluid in the presence of a hydroxylamine developing agent and a silver halide complexing agent, transferring said soluble silver complex by diffusion to the silver receptive layer of an image-receiving element in superposed relationship with said silver halide emulsion, forming at said silver receptive layer an image incorporating silver from said silver complex, and separating said image-receiving element from said photosensitive element.

Examples of suitable (poly)amino(poly)carboxylic acid sequestering compounds as well as details about the preparation of said sequestering compounds can be found in Ind. Chim. Belg. Tome XXI (1956) p. 338-346 and in Ind. Chim. Belg. Tome XXIII (1958) p. 1,105-1,115.

Particularly suitable (poly)amino(poly)carboxylic acids for use in acid or salt form in accordance with the present invention can be represented by the following non-limitative general formula:

wherein:

L stands for alkylene including substituted alkylene e.g., hydroxyalkylene, cycloalkylene including substituted cycloalkylene or alkylene interrupted by one or more hetero atoms, such as an oxygen atom,

x represents 0, 1 or 2,

R stands for lower alkylene e.g., methylene and ethylene including substituted lower alkylene e.g., alkylene substituted by alkyl, aryl, aralkyl, including substituted alkyl, aryl and aralkyl, and

each of R₁ and R₂ (the same or different) stands for hydrogen, lower alkyl including substituted lower alkyl, aralkyl including substituted aralkyl or aryl including substituted aryl; examples of substituted alkyl groups for R₁ and for R₂ are alkyl substituted with hydroxyl, halogen, alkoxy, carbamoyl, amino, substituted amino e.g., dihydroxyalkylamino, epoxy, carboxyl, sulpho, phosphono, mercapto, alkylmercapto, alkoxy carbonyl, a nitrogen-containing heterocyclic ring e.g., pyridyl and examples of substituted aryl groups and aralkyl groups for R₁ and/or R₂ are: aryl and aralkyl substituted by hydroxyl, halogen, alkyl, alkoxy, nitro, carboxyl and sulpho.

The following is a non-limitative list of examples of (poly)amino(poly)carboxylic acids corresponding to the above general formula:

ethylenediamine, N,N,N',N'-tetraacetic acid disodium salt

1,2-propylenediamine, N,N,N',N'-tetraacetic acid

ethylenediamine, N,N,N',N'-tetrapropionic acid

N-(2-hydroxyethyl)-ethylenediamine, N,N',N'-triacetic acid

N-(2-hydroxypropyl)-ethylenediamine, N,N'-triacetic acid

N-(2,3-dihydroxypropyl)-ethylenediamine, N,N',N'-triacetic acid

N,N'-di(2-hydroxyethyl)-ethylenediamine, N,N'-diacetic acid

diethylenetriamine, N,N,N',N'',N'''-pentaacetic acid

nitrilo triacetic acid

ethylenediamine, N,N'-di(o-hydroxyphenyl)acetic acid

di(2-hydroxyethyl)-amino acetic acid

2-hydroxyethyl-amino diacetic acid

1,2-amino cyclohexane, N,N,N',N'-tetraacetic acid

2,3-dihydroxypropyl-aminodiacetic acid

ethyleneglycol bis(2-aminoethyl)-N,N,N',N'-tetraacetic acid

N-(2-hydroxyethyl)-N'-(alpha-pyridinomethyl)-ethylenediamine, N,N'-diacetic acid

In a process for preparing silver transfer images according to the present invention wherein compounds corresponding to the above general formula are used, the said compounds are present in the photosensitive element. These compounds may be located in the silver halide emulsion layer of said element or in a layer in water-permeable relationship with said emulsion layer. They may be used in amounts varying between very wide limits, preferably, they are used in amounts comprised between 30 mg and 15 g per mole of silver halide.

The silver halide emulsions utilized in preparing photosensitive elements used in the present diffusion transfer system can be any of the conventional negative-type emulsions. Typical suitable silver halides include silver chloride, silver bromide, silver

bromide, silver chloroiodide, silver chlorobromide, silver chlorobromochloride, etc. These silver halide emulsions can contain spectral sensitizers, speed-increasing addenda, hardeners, coating aids, antifogants, plasticizers and the like conventional emulsion addenda.

The photosensitive silver halide element may also comprise in the silver halide emulsion layer or in a layer in water-permeable relationship with the said emulsion layer, compounds having a favorable effect on the maximum density of the image formed and/or in the speed of the photosensitive element. Examples of these compounds are the 1-aryl-3-pyrazolidinone compounds examples of which can be found in the application for "Silver Complex Diffusion Transfer Process" filed on even date herewith (=United Kingdom Patent application No. 52,572/69), as well as diamine or polyamine compounds and morpholine derivatives, typical examples of which are the compounds represented by the following formulas:

- a. $\text{H}_2\text{N}-\text{CH}_2-\text{CH}_2-\text{CH}_2-\text{NH}-\text{CH}_2-\text{CH}_2-\text{NH}_2$
25 b. $\text{H}_2\text{N}-(\text{CH}_2)_2-\text{NH}-(\text{CH}_2)_2-\text{NH}-(\text{CH}_2)_2-\text{NH}_2$
c. $\text{H}_2\text{N}-(\text{CH}_2)_2-\text{NH}-(\text{CH}_2)_2-\text{NH}_2$
d. $\text{H}_2\text{N}-\text{CH}_2-\text{CH}_2-\text{NH}-\text{CH}_2-\text{CH}_2-\text{OH}$

As previously noted, processing occurs with an alkaline processing liquid in the presence of a silver halide complexing agent and a hydroxylamine developing

20 agent. These agents are preferably present in the processing liquid itself although it is also possible to incorporate them in the photosensitive or image-receiving element. For instance, the hydroxylamine derivatives can be incorporated in the said elements in the 25 form of acid salts thereof e.g., in hydrochloride or hydrobromide form. When the developing and/or silver complexing agents are incorporated in the photosensitive and/or image-receiving element, the development of the exposed silver halide and the formation of the 30 silver complex of unexposed silver halide is activated when the alkaline processing fluid is spread as a thin layer between the photosensitive element and the image-receiving element.

Silver halide complexing agents suitable for use in 35 diffusion transfer processes are well known in the art and include alkali metal thiosulphates and thiocyanates, such as sodium thiosulphate and sodium thiocyanate. Silver halide complexing agents that are particularly suitable for use in accordance with the present 40 invention are cyclic imides for example barbituric acid, uracil and urazole as well as derivatives thereof, examples of which can be found in U.S. Pat. No. 2,857,276 mentioned above. Among the hydroxylamine developing agents that are particularly suitable, mention may 45 be made of the heterocyclic N-hydroxylamines such as N-hydroxymorpholine, N-hydroxy piperidine and N-hydroxy pyrrolidine, the primary and secondary N-lower alkyl hydroxylamines such as N,N-diethylhydroxylamine, the alkoxy-substituted derivatives thereof such as N,N-di(2-ethoxyethyl) hydroxylamine and N-ethyl-N-(2-ethoxyethyl)-hydroxylamine, the sulphone-hydroxylamines such as N-methyl-N-2-ethylsulphonyl-ethyl hydroxylamine and bis-2-(methyl-hydroxylamino)-ethyl sulphone and the aminoalkyl hydroxylamines such as N-methyl-N-2-dimethylaminoethyl-hydroxylamine. Further examples of such hydroxylamine derivatives can be found in the U.S. patent specifications referred to above.

60 The processing fluid comprises bases imparting to the fluid the required alkalinity. As examples of such bases mention may be made of alkali-metal hydroxides, e.g., sodium and potassium hydroxide, sodium carbonate, borax, sodium metaborate, trisodium phosphate, etc.

The fluid may further contain, or dissolve in its travel to the photosensitive element, other compounds which

are desired in the treatment of the photosensitive layer and in the production of the positive image in the image-receiving layer.

In silver complex diffusion transfer processes for in-camera processing, the processing fluid employed is relatively viscous, of the order of 1,000 to 200,000 centipoises at 20°C, so as to be easily controlled when spread. In order to obtain the desired viscosity, the liquid contains a thickening agent, preferably a water-soluble film-forming material such as water-soluble plastic so that when the liquid is removed from the processing layer by absorption and/or evaporation there remains a solid plastic film. The film-forming plastic may be any of the high molecular weight polymers which are stable to alkali and which are soluble in aqueous alkaline solutions e.g., hydroxyethylcellulose, starch or gum, polyvinylalcohol, the sodium salts of polymethacrylic acid and polyacrylic acid, sodium alginate, sodium carboxymethyl cellulose. As is known in the art, stripping of the silver halide element from the image-receiving element may separate the solidified layer of processing composition from the image-receiving element or may permit the layer of processing composition to remain in contact with the image-receiving element so that the solidified layer provides a protective coating over the image obtained.

The viscous processing fluid for use in in-camera processing is preferably confined within a hermetically sealed container or pod which is positioned between the photosensitive element and the image-receiving element and which is ruptured and releases its contents upon advancing the photosensitive element and image-receptive element between a pair of pressure-rollers. Such a container is impervious to the processing liquid and to the vapor of said liquid, and may be formed of a multilayer composite material comprising as inner layer in contact with the liquid, a material which is impervious to the liquid as intermediate layer a substance which is impervious to the vapor of said liquid and as outer layer a material merely serving as a backing or support. In its preferred form, the container is formed of a multilayer material whose inner layer is formed of a plastic such as polyvinyl acetal e.g., polyvinyl butyral, polymeric esters such as cellulose acetate, cellulose acetate butyrate, polyvinyl acetate, polyvinyl chloride, etc., said layer being backed by a metal foil e.g., a lead foil or lead-tin foil which is impervious to the vapors of said solution. The containers may be strengthened by a more rapid backing material such as kraft paper or a plastic such as polyvinyl acetate and polyvinyl chloride. More details as to the construction of such a rupturable container can be found amongst others in U.S. Pat. No. 2,634,886 of Edwin H. Land, issued Apr. 14, 1953.

The silver halide emulsion layer and/or the image-receiving layer may be coated on opaque or transparent supports. In this way it is possible to expose the photosensitive element from either side as desired and it is possible to form either reflection prints or transparencies.

The image-receiving layer of the image-receiving element preferably comprises mentioned, promoting precipitation of the silver from the transferred silver complex. Examples of such agents, called development nuclei or shortly nuclei, are well known and include sulphides, selenides, polysulphides, polyselenides, thioureas, thioacetamides, mercaptans, stannous halides, heavy metals or their salts and fogged silver halide. Sulphides of heavy metals such as of antimony,

bismuth, cadmium, cobalt, lead, nickel and silver are also suited. Lead sulphide and zinc sulphide as well as the complex salts thereof are especially effective either in themselves or mixed with thioacetamide, dithiobiuret and dithio-oxamide. Among the heavy metals silver, gold, platinum, palladium and mercury are to be mentioned preferably in colloidal form.

The development nuclei may be associated with a granular, inorganic, water-soluble, substantially chemically inert substance such as silica as vehicle for the said nuclei whereby aggregation of the precipitated silver is promoted.

In at least one layer of the image-receiving element other substances may also be incorporated which play a part in the formation of the diffusion transfer image e.g., black-toning agents, anti-yellowing agents, optical bleaching agents, softening agents, etc.

For in-camera processing the image-receiving element may be constructed as described in U.S. Pat. No. 2,823,112 of Edwin H. Land, issued Feb. 11, 1958. According to this United States patent specification the print-receiving element is so constructed that the viscous processing fluid separates therefrom and leaves no droplets or film of developing composition on the print-receiving layer. The image-receiving layer is thin, holding a mass of water so small that there is not tactful wetness. Moreover, by making the print-receiving layer so thin the tendency to curl is also avoided. Consequently, when peeled from the photosensitive element, which carries the viscous processing layer, the image-receiving element appears to be a dry sheet.

According to this United States patent specification a layer, which is substantially impervious to the processing liquid and which may be the liquid-impervious surface of a supporting sheet which is entirely formed of liquid-impervious material is provided between the silver precipitating layer in which the positive is formed, and the remainder of the image-receiving element. Further, the image-receiving layer is provided with a surface from which the viscous film of processing fluid may be readily stripped. Thus, according to said United States patent specification the outer surface of the image-receiving element contacting the layer of processing composition is so constituted as to have a lesser adhesion for the solid residue of the liquid processing composition than does the photosensitive element. As a result, the photosensitive element, when stripped from the image-receiving element, carries with it the residue of the processing composition. Further, between the image-receiving layer and the stripping layer an abrasion resistant coating may be provided.

According to this United States patent specification stripping of the silver halide element from the image-receiving element separates the layer of processing solution from the image-receiving element. However, as noted hereinbefore in order to provide the image-receiving element with a protective coating, it is also possible that upon stripping the layer of processing solution remains in contact with the said image-receiving element. Such stripping techniques are taught in U.S. Pat. No. 2,647,056 of Edwin H. Land, issued July 28, 1953.

The following examples illustrate the present invention. In these examples the value given for the speed are relative values, measured at density 0.5.

EXAMPLE 1

A photosensitive element was prepared which com-

prises a silver bromoiodide emulsion layer applied to a paper support and containing per kg an amount of silver halide corresponding to 60 g of silver nitrate and a (poly)amino(poly)carboxylic acid compound as listed in the table below in the amount given. After exposure, the photosensitive element together with an image-receiving element comprising a silver receptive layer containing development nuclei dispersed in a matrix of colloidal silica coated on a water-impervious base according to the practice described in U.S. Pat. No. 2,823,122 of Edwin H. Land, issued Feb. 11, 1958, were advanced in superposed relationship between a pair of pressure applying rollers to spread between them in a thin layer a processing composition comprising per liter:

sodium carboxymethyl cellulose	40 g
sodium hydroxide	35 g
uracil	75 g
N,N-di(2-ethoxyethyl)-hydroxylamine	40 ml

After a contact period of 36 seconds, the emulsion together with the layer of processing liquid was stripped from the image-receiving element to uncover the positive print.

The results obtained are listed in the table below.

TABLE

Compound added per kg of emulsion	D _{max}	D _{min}	Gamma	Speed (%)
none	1.55	0.04	1.50	100
1 g of compound 1	1.48	0.03	1.22	153
0.1 g of compound 1	1.52	0.03	1.37	130
0.1 g of compound 10	1.50	0.04	1.09	146
0.1 g of compound 12	1.52	0.03	1.32	142
0.1 g of compound 15	1.51	0.03	1.30	133
0.1 g of compound 25	1.53	0.03	1.44	124

These results show that the compounds of use according to the present invention have a favorable effect on the speed without causing a noteworthy decrease in maximum density of the image formed.

EXAMPLE 2

Example 1 was repeated with the difference that the photosensitive elements were processed directly after preparation and after having been stored for 5 days at 45°C and 15 percent of relative humidity.

The following results were attained.

Compound added per kg of emulsion	Fresh material			Stored material		
	D _{max}	D _{min}	Gamma Speed ma (%)	D _{max}	D _{min}	Gamma Speed ma (%)
none	1.57	0.03	1.73 100	1.59	0.03	1.63 87
50 mg of compound 10	1.53	0.03	1.33 139	1.58	0.03	1.47 112
100 mg of compound 10	1.56	0.03	1.50 136	1.51	0.03	1.11 127
200 mg of compound 10	1.54	0.02	1.57 136	1.48	0.03	1.21 130
50 mg of compound 12	1.55	0.03	2.03 136	1.56	0.03	1.40 115
100 mg of compound 12	1.54	0.03	1.70 139	1.56	0.03	1.46 118
200 mg of						

compound 12	1.54	0.03	1.49	139	1.50	0.03	1.24	127
50 mg of compound 15	1.56	0.02	1.82	121	1.59	0.04	1.59	106
100 mg of compound 15	1.55	0.03	1.70	136	1.58	0.04	1.55	109
200 mg of compound 15	1.55	0.03	1.51	136	1.55	0.03	1.40	121

EXAMPLE 3

Example 1 was repeated with the difference that the silver halide emulsion layer of the photosensitive element now comprises compound 24 in an amount of 1 g per kg of emulsion. The sensitometric results obtained, as compared with the results obtained when no compound 24 is present are the following:

Material	D _{max}	D _{min}	Gamma	Speed(%)
Comparison material	1.55	0.04	1.69	100
Material comprising compound 24	1.53	0.04	1.32	138

EXAMPLE 4

This example is analogous to example 3 with the only difference that the silver halide emulsion contains per kg in addition to 1 g of compound 24, 0.5 g of 1-phenyl-3-pyrazolidinone.

The following results were attained.

Material	Fresh material			Material stored for 5 days at 49°C/15% R.H.		
	D _{max}	D _{min}	Gamma Speed ma (%)	D _{max}	D _{min}	Gamma Speed ma (%)
Comparison material	1.55	0.03	1.80 100	1.57	0.03	1.90 85
Material comprising compound 24 and 0.5 g of 1-phenyl-3-pyrazolidinone	1.64	0.03	1.95 136	1.67	0.03	2.03 121
Material comprising 0.5 g of 1-phenyl-3-pyrazolidinone and no compound 24	1.65	0.03	1.54 153	1.66	0.06	2.51 35

When comparing these results with the results obtained in example 3 it appears that 1-phenyl-3-pyrazolidinone has a favorable effect on the maximum density of the image formed and that the gain in speed by the presence of compound 24 is maintained though 1-phenyl-3-pyrazolidinone when used alone has a marked desensitizing effect after storage.

EXAMPLE 5

This example is analogous to Example 1. The photosensitive element according to the invention now comprises in the silver halide emulsion layer 500 mg of compound 1 per kg of emulsion.

The following results were attained.

Material	Fresh material			Material Stored for 5 days at 49°C/15% R.H.		
	D _{max}	D _{min}	Gamma Speed ma (%)	D _{max}	D _{min}	Gamma Speed ma (%)
none	1.57	0.03	1.73 100	1.59	0.03	1.63 87
50 mg of compound 10	1.53	0.03	1.33 139	1.58	0.03	1.47 112
100 mg of compound 10	1.56	0.03	1.50 136	1.51	0.03	1.11 127
200 mg of compound 10	1.54	0.02	1.57 136	1.48	0.03	1.21 130
50 mg of compound 12	1.55	0.03	2.03 136	1.56	0.03	1.40 115
100 mg of compound 12	1.54	0.03	1.70 139	1.56	0.03	1.46 118
200 mg of						

Comparison material comprising 500 mg of compound 1	1.58	0.05	1.49	100	1.62	0.04	1.95	73
	1.55	0.03	1.43	140	1.55	0.03	1.45	141

EXAMPLE 6

By addition of 1-p-tolyl-4,4-dimethyl-5-ethoxy-3-pyrazolidinone, a compound as described and claimed in United Kingdom Patent application 52,572/69 referred to above, to the emulsion layer of the

5 approximately 10 percent).

EXAMPLE 8

From Example 5 it appears that compound 1 has a favorable effect on the sensitivity without having a noteworthy influence on the maximum density of the image formed.

10 The results below show that when per kg of emulsion an amine is added in the amount given in the table below, in addition to 500 mg of compound 1, the speed can still be increased by approximately 25 percent.

Compound added per kg. of emulsion	D _{max}	D _{min}	Gamma	Speed percent
500 mg. of compound 1	1.59	0.04	1.34	100
500 mg. of compound 1 plus 100 mg. of H ₂ N-CH ₂ CH ₂ NHCH ₂ CH ₂ OH	1.55	0.04	1.04	126
500 mg. of compound 1 plus 100 mg. of H ₂ N-CH ₂ -CH-CH ₂ -NH ₂	1.54	0.05	1.10	128
OH				
NH ₂	1.55	0.05	1.00	123
500 mg. of compound 1 plus 100 mg. of H ₂ N-(CH ₂) ₈ -CH-COOH-2HCl	1.55	0.05	1.00	123

photosensitive element according to the invention as described in Example 5 in an amount of 100 mg per kg of emulsion, the speed is still further increased.

This is proved by the following results.

Material	Fresh material			Material stored for 5 days at 49°C/15 % R.H.		
	D _{max}	D _{min}	Gamma	D _{max}	D _{min}	Speed ma (%)
comparison material comprising 500 mg of compound 1	1.34	0.03	1.09	100	1.31	0.03
material comprising 500 mg of compound 1 and 100 mg of the 3-pyrazolidinone compound	1.35	0.03	1.17	129	1.42	0.03
				1.14	75	

EXAMPLE 7

Example 6 is repeated with the difference that now 45 per kg of emulsion 2 g of 1-phenyl-4,4-dimethyl-5-ethoxy-3-pyrazolidinone is used instead of 100 mg of 1-p-tolyl-4,4-dimethyl-5-ethoxy-3-pyrazolidinone.

The following results were attained with fresh material.

Material	D _{max}	D _{min}	Gamma	Speed(%)
Comparison material comprising 500 mg of compound 1	1.52	0.04	1.35	100
material comprising 500 mg of compound 1 and 2 g of the 3-pyrazolidinone compound	1.67	0.03	1.90	142

These results also prove that the speed can still be further increased by 40 percent by adding to the emulsion in addition to the (poly)amino(poly)carboxylic acid a compound as described and claimed in United Kingdom Patent application 52,572/69, the maximum density of the image formed also being increased (by

25 We claim:

which comprises the steps of image-wise exposing a photosensitive element containing a silver halide emulsion layer, developing the exposed silver halide and forming a soluble silver complex of unexposed silver halide by treating the said silver halide emulsion layer 30 with an alkaline processing liquid in the presence of a hydroxylamine developing agent and a silver halide complexing agent, transferring said soluble silver complex by diffusion to an image-receiving element in superposed relationship with said photosensitive element, 35 forming at an image-receiving layer of said image-receiving element an image incorporating silver from said silver complex, and separating said image-receiving element from said photosensitive element, the use of a photosensitive element which includes in the silver halide emulsion layer or a hydrophilic colloid layer in water-permeable relationship with the said emulsion layer a (poly)amino(poly)carboxylic acid compound in the acid form or in the form of a water-soluble salt.

present in the silver halide emulsion layer of the photosensitive element in an amount of from about 30 mg to 15 g per mole of silver halide.

6. A process according to claim 1, wherein said photosensitive element also includes an 1-aryl-3-pyrazolidinone compound.

7. A process according to claim 1, wherein said photosensitive element also includes a diamine or polyamine compound.

8. The process according to claim 1 wherein said (poly)amino(poly)carboxylic acid compound is ethylenediamine,N,N,N',N'-tetraacetic acid disodium salt.

9. The process according to claim 1 wherein said (poly)amino(poly)carboxylic acid compound is 15

16

ethylenediamine, N, N' - di(O - hydroxyamino (poly) carboxylic acid compound is ethylenediamine, N, N-di(O-hydroxyphenyl acetic acid.

10. The process according to claim 1 wherein said (poly)amino(poly)carboxylic acid compound is 2-hydroxyethyl-amino diacetic acid.

11. The process according to claim 1 wherein said (poly)amino(poly)carboxylic acid compound is ethyleneglycol bis(2-aminoethyl)-N,N,N',N'-tetraacetic acid.

12. The process according to claim 1 wherein said (poly)amino(poly)carboxylic acid compound is 2-hydroxy-3,5-dichlorobenzylamino-N-acetic acid sodium salt.
